CLOSURE MEANS FOR HOLLOW TYPE PROPELLER BLADES

Arthur H. Jackson, Jr., West Hartford, Conn., assignor to United Aircraft Corporation, East Hartford, Conn., a corporation of Delaware

Application May 23, 1952, Serial No. 289,633

3 Claims. (Cl. 170—159)

The present invention relates to aeronautical propeller blades and, more specifically, to improvements in a closure member or cuff therefor which is adapted particularly for application to the fairing area at the inboard end of a hollow, core-and-shell type propeller blade.

It is the general aim of the invention to provide a blade cuff which will effectively close the inboard end of the blade to the passage of moisture and which will be constructed and arranged to provide an airfoil extension on the blade to increase its efficiency and to increase the cooling air stream to the aircraft engine.

A more specific object is to provide a cuff having the foregoing characteristics and which includes filler means adapted particularly to improve the bond between the blade shell, the cuff, and the core.

Other objects and advantages of the invention will become apparent to those skilled in the art from the following description of the drawing which, by way of preferred example only, illustrates one specific embodiment of the invention.

In the drawing:

Fig. 1 is a foreshortened elevational view of an aeronautical propeller blade which includes the cuff of the present invention;

Fig. 2 is a transverse sectional view of the blade taken on line 2—2 of Fig. 1;

Fig. 3 is a transverse sectional view taken on line 3—3 of Fig. 1;

Fig. 4 is a perspective view of a preformed pack used in forming the cuff of the blade; Fig. 5 is an enlarged transverse sectional view similar to Fig. 2 but showing only the leading edge portion of the blade; and Fig. 6 is a transverse sectional view taken on line 6—6 of Fig. 1.

At the outset it should be understood that the cuff or closure member of the present invention is particularly adapted for application to core-and-shell type propeller blades. Such blades are well known in the art and will be only briefly described here to complete the understanding of the present invention. The blade, exclusive of the cuff, shown in the drawing is typical of the type mentioned in that it comprises two main parts, namely, a core 10 and a shell 12. It is conventional to provide the shank end of the tubular core with races 14 by means of which the core can be retained within a hub (not shown). The extending or outboard portion of the core 10 is flattened into general airfoil configuration and the one-piece airfoil forming shell 12 is enfolded over the flattened portion of the core and secured thereto as by brazing with the shank of the core extending through the open inboard end of the shell.

As clearly shown in Fig. 1, the leading and trailing edges 16 and 18 of the shell overhang the corresponding edges 20 and 22 of the core in spaced relation thereto. The marginal edges of the open inboard end of the shell 12 extend from the leading and trailing edges 16 and 18 in substantially straight lines at substantially equal acute angles to the longitudinal center line of the core to define a longitudinally extending projection 24 of the shell which is also brazed to the core. A cuff for closing the inboard end of the shell is indicated generally by the numeral 26 and it is this cuff, to be described in detail later, which incorporates the improvements of the invention.

It is conventional practice to fill the space 28 extending from the open inboard end of the shell to the outboard end of the blade and between the leading edges of the shell and core and the space 30 extending from the open

2

inboard end of the shell to the outboard end of the blade and between the trailing edges of the core and shell with a rubber-like material to reinforce the shell and prevent undesired movements and vibration thereof. The preferred rubber-like material is nylon reinforced synthetic sponge which is introduced to the spaces 28 and 30 in pellet form. The application of sufficient heat, in what is called a "cure," will cause the pellets to form into a substantially homogeneous mass bonded or vulcanized to the core and shell.

In providing for the cuff of the present invention, the aforementioned pellet filler is terminated short of the open inboard end of the shell and preformed bulkheads 32 and 34 are inserted through the open inboard end of the shell and disposed within the shell adjacent the leading and trailing edges, respectively. Thus the bulkheads 32 and 34 limit the inboard extent of the pellet filler in the spaces 28 and 30, as shown in Fig. 1. The bulkheads 32 and 34 are of essentially the same composition as the pellets, but are preformed and precured to form relatively dense packs arranged to snugly fit between the core and shell. The bulkheads prevent expansion of the pellet filler toward the inboard end of the shell while the pellets are being cured.

The airfoil configuration of the cuff is provided by two filler packs 36 and 38 which are preformed to fit the leading and trailing edges, respectively, of the core with their outer end portions extending into the open end of the shell. The packs 36 and 38 are relatively dense and rigid, but can be compressed sufficiently for insertion within the shell to engage the bulkheads 32 and 34, and the packs 36 and 38 comprise substantially the same material as the pellet filler and will react to the cure in the same manner as the pellets.

To make the built up cuff water tight and for reinforcement purposes, the exposed portions of the packs 36 and 38 and the end portion of the shell are provided with a three layer wrapping.

The innermost wrapper 40 comprises a thin sheet of rubber-like material generally similar to the aforescribed filler elements and packs. The middle wrapper 42 is a five ply laminated sheet of rubber and fiberglass layers which reinforces the cuff. The outer wrapper 44 is a relatively thick sheet of synthetic rubber which prevents the ingress of moisture. The inner and middle wrappers 40 and 42 are each trimmed on the lines 46 and 48 so that the outer wrapper will extend thereover. The open end of the cuff is closed at the leading and trailing portions, respectively, by relatively thick sheets of synthetic rubber 50 and 52 fitted within the open end of the outer wrapper 44 as shown in Fig. 6. The sheet 50 is located in the open end of the wrapper 44 at the leading edge portion thereof and abuts preformed pack 36 and extends transversely of the blade to the core 10. The sheet 52 is located in the open end of the wrapper 44 at the trailing edge portion thereof and abuts the pack 38 and extends transversely of the blade to the core 10. To assure a completely moisture proof cuff, a rubber sleeve 54 embraces the core adjacent the shank end thereof and extends into the inboard end of the cuff to be vulcanized to the core and to the cuff closure members 50 and 52 when heat is applied during the cure.

The "cure" is accomplished by placing the blade and cuff within restraining dies and applying heat sufficient to vulcanize the previously described rubber-like elements of the filler and cuff. The cuff then becomes a molded integral piece bonded to the core and to the shell. After the application of heat, the blade and cuff are permitted to cool. In cooling, the packs 36 and 38 take a set, tending to shrink or contract, thereby drawing the cuff tighter to the core. This shrinkage also tends to separate the said packs from the shell. It has been observed that there is insufficient shrinkage within the confined space at the trailing edge to cause separation. It has been discovered that separation at the leading edge can be prevented by forming the pack 36 with a plurality of longitudinally disposed slots.

The said slots extend through the pack 36 from the leading edge of the core to the leading edge of the shell in the portion of the pack which fits within the shell. It

has been found that the shrinkage of the pack 36 will widen the slots, but the pack will not separate from the shell. A porous rubber-like sheet 56 is disposed within each of the above described slots before the cure, and when the pack shrinks the sheets expand to fill any voids and thus maintain the integrity of the pack. The sheets 56 are preferably more elastic than the preformed packs and pellet filler components and because of their porous construction do not take a set or shrink as do the packs and thus the said sheets are enabled to expand within the slots as the pack 36 shrinks.

It will be understood that the aforescribed cuff, in addition to providing a highly desirable moisture proof closure for the inboard end of the shell, also improves the operating characteristics of the blade by extending the airfoil length thereof. The said airfoil extension is advantageous for the additional purpose of increasing the cooling air stream to the aircraft engine.

It will be further understood that the scope of the invention is not limited to the specific embodiment shown except as indicated by the claims which follow.

I claim:

1. An aeronautical propeller blade comprising in combination, an elongated core having a shank end, a sheet metal airfoil-forming shell surrounding and supported on said core and having an open end through which the shank end of the core extends; said open end of the shell having leading and trailing portions overhanging the core, a rubber-like pack extending into the open end of the shell adjacent the shank of the core and adapted to be bonded to the core and shell upon the application of heat, said pack having at least one slot extending between said core and said shell to permit said pack to shrink as a result of heat application without separating from said core or said shell, and a readily expansible rubber-like sheet disposed in the said slot.

2. An aeronautical propeller blade comprising in combination, an elongated core having a shank end, a sheet metal airfoil-forming shell surrounding and supported on said core and having an open end through which the

shank end of the core extends, said open end of the shell having leading and trailing portions overhanging the core, and a rubber-like pack extending into the open end of the shell adjacent the shank of the core and adapted to be bonded to the core and shell upon the application of heat, said pack having a plurality of slots extending between the core and the shell, and a readily expansible rubber-like sheet disposed in each of said slots.

- 10 3. An aeronautical propeller blade comprising in combination, an elongated core having a shank end, a sheet metal airfoil-forming shell surrounding and supported on said core and having an open end through which the shank end of the core extends, said open end of the shell having leading and trailing portions overhanging the core, a first airfoil-forming pack extending into said open end of the shell at the leading portion thereof, a second airfoil-forming pack extending into the open end of the shell at the trailing portion thereof, each of said packs being arranged to extend between said shell and said core and being adapted to bond to said shell and said core upon the application of heat, means on said first pack defining a plurality of longitudinal slots extending between said core and said shell, and a plurality of readily expansible rubber-like sheets each supported within a slot in the pack.
